6 Claims

This invention relates to means for electrically charging particles of microscopic size, and more particularly to means whereby such charging is accomplished by subjecting the particles to the influence of a high intensity ion beam.

Electrostatically charged microscopic particles find use in the laboratory for simulating micrometeoroids. One type of apparatus for electrostatically charging microscopic particles by means of an ion beam is disclosed by J. F. Vedder in an article entitled, "Charging and Acceleration of Microparticles," published in Review of Scientific Instruments, vol. 34, No. 11, pp. 1175-1183, dated 1963. In that apparatus the particle to be charged is trapped in an electrodynamic containment system and bombarded by a low intensity ion beam. The parameters of the containment system are adjusted to increase the charge on the particle. When the particle is fully charged, it is expelled from the charging chamber. The main disadvantage of the foregoing method is the extremely low charging rate; it is estimated that only four particles a day can be charged in that manner.

The present invention provides apparatus whereby a fine beam of microparticles is injected into a high intensity ion beam substantially coaxially therewith. The ion beam induces a surface field on the microparticles whose magnitude is proportional to the time during which the particles remain within the ion beam. Thereafter, the ion beam is separated from the charged particle beam.

In the drawing, FIG. 1 is a diagrammatic view of apparatus for charging microparticles by means of an ion beam according to the invention; and

FIG. 2 is a schematic of a variable D.C. supply used in the apparatus of FIG. 1.

Referring to FIG. 1 of the drawing, there is shown a vacuum chamber 10 containing a particle injector 12 for accelerating microns size particles along a first axis 14 in the direction indicated by the arrow 15. The particles may be made of iron, carbon or aluminum, for example, and may range in size from fractions of a micron to a few microns in diameter. The particles leaving the particle injector 12 may be initially charged to electric field strengths of the order of 10^8 volts per meter and have a velocity up to a few hundred meters per second. However, as will be apparent, the initial field strength is not critical, because of the relatively large final field strength that will result from interaction with the ion beam. However, at least a nominal field strength is necessary to focus and align the particles relative to the ion beam. The particle injector 12 may comprise a particle accelerator of the kind disclosed in the article by J. F. Friichtenicht, published in the Review of Scientific Instruments, vol. 3, No. 2, pp. 209-212, February 1962, and entitled, "Two-Million-Volt Electrostatic Accelerator for Hypervelocity Research," or in the article by H. Shelton, C. D. Hendricks, Jr., and R. F. Wuerker, published in the Journal of Applied Physics, vol. 31, No. 7, pp. 1243, July 1960, and entitled, "Electrostatic Acceleration of Microparticles to Hypervelocities." A suitable particle injection rate is about 10 particles per second.

The particles leaving the particle injector 12 are focussed by a particle beam lens 16 into a fine particle

beam 18, indicated by the arrows, having a diameter, for example, of about 1 millimeter. The lens 16 is of conventional type well known to those skilled in the art of electron optics.

A pulsed ion source 20 generates a high intensity stream of ions along a second axis 22 in the direction indicated by the arrow 23. The ions are focussed by an ion beam lens 24 into a fine ion beam 26, indicated by the arrows. The ion source 20 is of conventional type, and may be one of the kind disclosed in the articles entitled, "Production of Low Divergence Positive Ion Beams of High Intensity," by N. B. Brooks, T. H. Rose, A. B. Wittkower, and R. P. Bastide, Review of Scientific Instruments, vol. 35, No. 7, pp. 894-901, July 1964. The ion beam lens 24 is also of conventional type known to those skilled in the art of electron optics. The ion beam 24 may, for example, have an energy of 50,000 electron volts, a current of 100 microamperes and a beam diameter of about eight millimeters.

Spaced downstream from the particle beam lens 16 and ion beam lens 24, are a pair of spaced apart particle beam deflecting plates 28 and 30 laying on opposite sides of the ion beam axis 22. The plates 28 and 30 are adapted to have a direct current voltage applied to them by a variable D.C. supply 31 that may be varied from about 1 to 2 kilovolts. When the particle beam 18 is directed between the plates 28 and 30, the electric field therein acts to deflect the particle beam 18 so that it coincides with the ion beam axis 22. By varying the voltage on the plates 28 and 30, the particle beam 18 may be deflected as to lie parallel with the ion beam axis 22. By moving the plates 28 and 30 longitudinally in either direction parallel to the ion beam axis 22, the axis of the particle beam 18 may be made to coincide with the ion beam axis 22.

A particle detector 32 is disposed in the path of the ion beam 26 and particle beam 18. The particle detector 32 may be one of the kind disclosed in the above-identified Shelton et al. article. When a particle passes through the particle detector 32, the latter generates a rectangular voltage pulse whose amplitude is proportional to the charge on the particle and whose time duration is equal to the time of flight of the particle through the detector 32.

The rectangular voltage pulse from the particle detector 32 is fed to a discriminator 34 which differentiates the rectangular voltage pulse and generates a trigger pulse coincident with the trailing edge of the rectangular pulse. The discriminator 34 may be one of the kind disclosed by C. B. Ward and C. M. York in Nuclear Instruments and Methods, vol. 23 (1963), pp. 213-217.

The trigger pulse from the discriminator 34 is fed simultaneously to first and second one shot multivibrators 36 and 38 that generate positive rectangular pulses of equal time duration. The multivibrators 36 and 38 may be of the kind disclosed in the textbook by J. Millman and H. Taub, entitled, "Pulse, Digital, and Switching Waveforms," chapter 11, published by McGraw-Hill, New York, 1964.

The first multivibrator 36 drives a high voltage pulse generator 40 whose output is fed to the extraction electrode of the ion source 20, thereby turning on the ion beam 26 for the period of the first multivibrator 36. The high voltage pulse generator 40 may be one of the kind disclosed in the article entitled, "Transistor Circuit Pulses 1000 Volts," by D. O. Hansen, Electronics, vol. 38, No. 18, dated 1965.

When the ion beam 26 is turned on, it overtakes the particle that just exited the particle detector 32 in a charging region identified by broken lines 56. In the charging region 56, the particle is subjected to the charging influence of the ion beam 26. While it is within the ion beam 26, the surface field strength of the particle is increased at a constant rate, regardless of the size of the particle. The final field strength reached on the particle is determined by

the time that it stays within the beam. The ion beam 26 subjects the particle to an electric field which tends to displace the particle radially, and when the particle moves out of the ion beam 26 the charging process ceases. Thus, the closer to the ion beam axis 22 the particle is injected, the longer will be the charging time before the particle is deflected out of the ion beam 26.

The time required for the particle to reach a specified surface field is inversely proportional to the ion beam current density. The maximum obtainable particle surface field strength varies as the third root of the ion beam velocity and also as the third root of the particle diameter. An ion beam of 100 microamperes current and beam diameter of 8 millimeters will increase the surface field strength of an iron particle of 2 microns diameter by 10^8 to 10^9 volts per meter, while a 10 ampere ion beam will increase the field strength of the same particle by up to 4×10^{10} volts per meter.

After the particle is charged the ion beam 26 is turned off and the voltage is reapplied to the particle deflecting plates 28 and 30 so that the next particle will be deflected onto the ion beam axis 22. The charging period is determined by the duration of the multivibrator pulses. When the multivibrator pulses terminate, the ion beam 26 automatically turns off and the particle beam deflection voltage is restored.

The charged particle and the ion beam 26 pass through a D.C. magnetic field region, which may be provided by a permanent magnet 58. The D.C. magnetic field, which has a strength of 5 to 10 kilogauss, has a direction perpendicular to the ion beam axis 22, as illustrated by arrow, heads 60 emanating from the plane of the drawing. The magnetic field 60 deflects the ion beam 26 into a Faraday cup 62. The Faraday cup 62 may include an electrometer for measuring the ion beam current, from which the current density of the ion beam 26 may be calculated. Because of the lower charge to mass ratio and lower velocity of the charged particle, the magnetic field has no effect on the charged particle, and the particle beam 18 and ion beam 26 are thereby separated from one another. The particle beam 18 may then be fed to a utilization device, not shown.

The embodiments of the invention in which an exclusive property or privilege is claimed are defined as follows:

1. Particle charging apparatus, comprising:
means for producing and accelerating a beam of micro-particles along an axis;
means for producing an ion beam that intercepts said microparticles in the same direction along said axis so as to impart surface charge to said microparticles;

and means for separating said ion beam from said charged microparticles.

2. The invention according to claim 1, and further including means for detecting particles traversing a first region;

and means responsive to said detecting means for causing said ion beam to intercept said particles in a second region beyond said first region.

3. The invention according to claim 2, and further including means forming a region of magnetic field beyond said second region and traversed by said particle and ion beams for deflecting said ion beam from the path of charged particles.

4. Particle charging apparatus, comprising:
means for producing and accelerating a beam of micro-particles directed along a first axis;

means for producing an ion beam directed along a second axis;

means for deflecting said microparticle beam into coincidence with said ion beam along said second axis and in the same direction thereof, whereby microparticles within said ion beam receive surface charge therefrom;

and means for separating said ion beam from said charged microparticles.

5. The invention according to claim 4, and further including means in the path of said deflected microparticle beam for sensing the deflected microparticles and for energizing said ion beam producing means to cause the ion beam to intercept said deflected microparticles after they traverse said microparticle sensing means.

6. The invention according to claim 5, wherein said deflecting means are located in the path of said ion beam along said second axis, and further including means responsive to said microparticle sensing means for de-energizing said microparticle deflecting means during traversal by said ion beam.
